UNITED STATES PATENT OFFICE

2,104,894

ELECTRIC CONTROL DEVICE FOR BLOCK PRINTING MACHINES

Oscar Brophy, Philadelphia, Pa.

Application June 23, 1936, Serial No. 86,760

24 Claims. (Cl. 101—198)

My invention relates to block printing machines for printing linoleum rugs and felt base goods and the like. Said machines have reciprocating printing heads, as illustrated in the 5 United States Patent to Eisenhardt, No. 476,135, issued May 31, 1892. Machines of this type advance a strip of goods intermittently below printing heads, and the heads are of standard size for printing sections of goods equal to 18" and 10 each operation, or movement, of the machine advances the goods one 18" section of the goods.

My invention particularly relates to improvements in an electric control device for block printing machines. The control device is adapted for selecting the printing heads which are 15 to be operated, or held inoperative, for changing the sizes of the rugs to be printed.

The object of my invention is to provide novel 20 means for latching the printing heads out of printing operation and automatically controlling said latching means.

A further object is to provide a control device 25 having a novel latch operating device including a mechanically reciprocating part, a freely movable bearing arm interposed between said part and the latch, and locking means mounted upon the bearing arm for locking the latter with said part for engaging the latch with the printing head.

A further object is to mount an electro- 30 magnetic device upon the bearing arm for operating the locking means with the reciprocating part, and provide means between the bearing arm and the latch for yieldingly moving the latter into operative position.

A further object is to provide a control device 35 having a novel control belt for operating the latch operating means.

A further object is to provide a control belt 40 which is a moving miniature representation of many sections of the goods to be printed by the printing heads, whereby the operator will have exposed to his view a large surface of the control device containing several repeats of the rug patterns, and representing a large number of sections 45 of the goods before said sections pass adjacent to the printing heads, thus providing sufficient time for the operator to make changes in the control device for changing the arrangement 50 and sizes of the rugs to be printed.

A further object is to provide a control device 55 including an endless belt movable at a speed proportional to the speed of the goods, and construct the belt of transverse plates mounted in hinged relation to each other. Each plate forming a sec-

tion of the belt which is proportional to an 18" section of the goods.

A further object is to provide detachable cam blocks upon the belt for actuating switches for controlling electric circuits which in turn control the latch operating devices.

A further object is to provide means by which the cam blocks may be readily attached in different positions upon the belt so as to travel with the belt in any desired column and operate 10 certain switches for controlling different printing heads, whereby rugs of any size may be printed by simply varying the number of cam blocks used to control the heads for printing the field sections of any rug.

A further object is to provide a signal device 15 arranged to be actuated by signal cam blocks detachably mounted upon the belt, for indicating where the goods are to be cut to form lengths suitable for entering a drying rack of a predetermined length, and also indicate to the operator the sections upon the belt where one rug must be provided with a finishing border cam block, and the next successive section of the belt must be provided with a starting border cam 20 block, which result may be readily accomplished by rearranging the cam blocks.

A further object is to provide mercury switches 25 for controlling the circuits which in turn control the latch operating devices, and also provide pivoted bearings carrying the mercury switches and actuated by the cam blocks upon the belt.

A further object is to provide novel means for 30 mounting the bearings carrying the mercury switches, whereby they may be readily positioned to be engaged by the cam blocks in any desired column in which said blocks are advanced by the belt.

These together with various other novel features of construction and arrangement of the 35 parts, which will be more fully hereinafter described and claimed constitute my invention.

In the accompanying drawings; Fig. 1 is a side elevation, partly in section, of a portion of a 40 printing machine embodying my invention.

Fig. 2 is a perspective view showing diagrammatically my improved latch operating device.

Fig. 3 is an enlarged plan view of the control device shown in Fig. 1, partly in section.

Fig. 4 is an enlarged transverse vertical section 45 on line 4—4 of Fig. 3.

Fig. 5 is a vertical section on line 5—5 of Fig. 4.

Referring to the drawings, in which like reference characters refer to like parts, 10 represents the frame of a standard type of printing 50

machine. Printing heads 12, each carrying a printing block 13, are provided for printing a strip of goods 15, advanced intermittently over a table 16, and supported upon the frame 10.

5 The heads 12 are secured upon head slides 18 located on opposite sides of the frame and are slidably vertically in guides 20. The slides 18 each have a roller 21 which is engaged by a cam 22 for lifting the heads 12. The cams 22 are 10 secured upon opposite ends of shafts 23, mounted upon the frame 10. The shafts 23 each have a bevel gear wheel 24 secured thereon and rotated by means of suitable gearing 27, driven by a main shaft 25, in the usual manner.

15 When it is desired to omit the printing operation of any head, the head is held in the elevated position by latches 26, which engage projections 28, secured upon the slides 18. There are two latches 26 for each head. A shaft 30 is 20 rotatably mounted upon the frame 10, and the latches are rigidly secured upon the opposite ends of said shaft which project beyond the sides of the frame 10.

25 My novel latch operating device 31 comprises a cam arm 32, which is loosely mounted upon the shaft 30 and its free end is engaged by a second cam 33 secured upon the shaft 23. A bearing arm 35 is loosely mounted upon the shaft 30, carrying the latches 26. A hook 36 is formed upon 30 a lever 37 which is pivotally mounted upon a pin 38 secured upon the bearing arm 35. The hook 36 is adapted to engage a pin 40 secured upon the cam arm 32. A weighted arm 39 of the lever 37 tends to hold the hook 36 out of engagement with 35 the pin 40, and against a stop pin 41, as shown at the right hand portion of Fig. 1.

When the hook 36 is released from the pin 40 the cam arm 32 may be moved by the cam 33 without moving the bearing arm 35, and the 40 latches 26 will not engage the projections 28, thus allowing the head to be operated by the cams 22 for printing upon the goods.

45 A clamp head 45, see Fig. 2, is rigidly secured upon the shaft 30, carrying the latches. A plate 45 spring 46 is secured in the clamp head 45 and the free end of the spring 46 is adapted to be engaged by a pin 47, secured on the bearing arm 35. When the hook 36 is engaged with the pin 40 the bearing arm 35 will be moved with the 50 cam arm 32, and the pin 47, on the bearing arm 35, will move the spring 46, which latter will rotate the shaft 30 and swing the latches 26 into contact with guide plates 49, and when the head is moved adjacent to its highest position, the 55 spring 46 will force the latches into engagement with the projections 28 and hold the printing heads in the elevated position, during one complete revolution of the cams 22 and 33. At the completion of the revolution the cams 22 will 60 lift the head slides 18 sufficiently to release the latches 26 from the projections 28, so that weight 48, shown in Fig. 2, secured upon the shaft 30, will tend to turn the latter and move the latches away from the projections 28, unless the hook 65 36 is still held in engagement with the pin 40, as hereinafter described, in which case the head 12 will be held in the elevated position by the latches 26 during another revolution of the cams 22 and 33.

70 The hook 36 is moved into engagement with the pin 40 by the action of a solenoid 50, secured to the bearing arm 35. The solenoid 50 may be of any well known construction. The movable armature 51 of the solenoid is pivotally connected 75 to the weighted arm 39 of the lever 37.

When the solenoid 50 is energized, the hook 36, on the lever 37, will be moved into engagement with the pin 40, and the bearing arm 35 will be moved with the cam arm 32. The bearing arm 35 is held in an adjusted position for 5 insuring the engagement of the hook 36 with the pin 40 by an eccentric stop sleeve 53, which is secured upon a cross shaft 54, rotatably mounted in the frame 10. A guide plate 55, shown in Fig. 2, is secured upon the bearing arm 35 and projects along one face of the cam arm 32 for guiding the parts in proper relation.

Each hook lever 37 is moved by a solenoid 50, which latter is connected in an electric circuit 56 including a switch 58 adapted for closing said 15 circuit and energizing the solenoid 50 for locking the hook 36 with the pin 40, thus engaging the latch 26 with the projection 28 for holding the printing head 12 out of operation.

A control device 60, including the switches 58, 20 25 is provided for actuating the latch operating devices 31 for engaging and disengaging the latches 26 of the several heads 12.

The control device 60 is located upon one side of the frame 10 and adjacent to the end of the 25 machine into which the goods 15 enter the machine to be printed. The control device 60 comprises an endless belt 61 formed of transverse plates 62, having their ends mounted upon parallel chains 63. The chains are mounted upon 30 wheels 64 and 65, secured upon shafts 66 and 67, which are rotatably mounted in bearings 68 and 69 secured upon a bearing frame 70. The wheel 64, as shown in Figs. 4 and 5, is driven by a worm wheel 72 secured upon shaft 66. The 35 wheel 72 meshes with a worm 73 secured upon a vertical shaft 74. As shown in Fig. 1 the shaft 74 is driven through suitable gears 75, 76, 77 and 78 from the main shaft 25 for advancing the belt 61 in timed relation with the advancement of 40 the goods 15 through the machine.

The bearing frame 70 is supported upon the frame 10 by brackets 79, shown in Fig. 1. A table 80 is mounted upon the frame 70 and also secured to the frame 10 by plates 81. The table 45 80 forms a support for tracks 82 on which the straight run of the belt 61 is supported. Vertical bearing plates 84 and 85 are secured upon the table 80 and extend along opposite sides of the belt 61 for a distance equal to about one-half the 50 distance between the wheels 64 and 65, on which the belt is mounted. Said plates 84 and 85 form supports for the opposite ends of a series of transverse shafts 86, positioned above the belt so that the latter may pass below said shafts and 55 operate a switch 58 located upon each shaft 86, for controlling the operation of the printing heads.

There is a switch 58 and a solenoid 50 included in each circuit 56 for controlling and operating 60 the latches 26 for each printing head 12. Said shafts 86 are detachably secured in the bearing plate 84 by thumb screws 87, shown in Figs. 3 and 4. Handles 88 are secured upon the shafts 66 for quickly removing the shafts when changing 65 the position of the switches.

The chains 63 of the belt 61 are formed of links 90 pivoted together by pins 91, as shown in Figs. 3 to 5. The links 90 have extension brackets 92 thereon to which the ends of the transverse plates 70 62 are secured by bolts 93 and said plates 62 are supported by the brackets 92.

The transverse plates 62 of the belt extend parallel to each other and form a flat surface throughout the straight run of the belt. Said 75

plates 62 are preferably formed of aluminum strips each $5\frac{1}{2}$ " in width.

The entire length of the belt 61 is formed of the hinged sections, or plates 62, each occupying 5 $5\frac{1}{2}$ " throughout the length of the belt. Each section of the belt corresponds to an 18" section of the goods to be printed. The length of the belt is equal to a multiple of 64 sections or plates 62, when the goods are to be cut into strips each 10 96' long, and containing 64 sections and adapted to be received in a drying rack of that length. If the printing machine is to be used in connection with a drying rack of a different size, then the 15 number of plates 62 forming the belt will be varied accordingly.

Each plate 62 is formed with slots 95 to provide means for detachably mounting cam blocks 96 upon the belt, for operating the switches 58. Upon the under surface of each cam block 96 is 20 a double end plate spring 97, shown in Fig. 4, adapted to enter a slot 95 of a plate 62 and engage the plate 97 for detachably securing the cam block 96 upon a plate 62.

A cam block 96 may be secured in any one of 25 the several slots 95, which latter are arranged at given intervals throughout the length of each transverse plate 62. The cam blocks 96 will be carried by the belt in columns for operating successively the different switches 58, which switches 30 are positioned immediately above a particular column of the belt for controlling certain printing heads 12 for printing starting border sections of the rugs, or heads for printing field sections, or heads for printing finishing borders, or double 35 borders, or center designs of rugs. By shifting the cam blocks 96 from one column of the belt to another column any desired order may be followed for printing rugs of different sizes.

The switches 58, which are actuated by the cam 40 blocks 96, are each operated by an arm 98, one end of which arm is rigidly secured upon a sleeve 99, which is loosely mounted upon a shaft 86. The sleeve 99 projects beyond one side of the arm 98 and forms a bearing for a clamp block 100, 45 which latter is adjustably secured in any desired radial position on the sleeve 99 by a set-screw 101.

The clamp block 100 has an extension plate 102 thereon, which plate is provided with a spring 50 clip 103 for holding a mercury tube switch 105, of any well known construction. Said mercury tube switch forms part of the switch 58.

The free end of the arm 98 is provided with a 55 roller 106 which normally rests upon the flat surface of the belt plates 62, as shown in Fig. 5, and positions the switch tube 105 at an angle inclined to the top surface of the belt 61, so that the mercury in the tube will form an electrical connection between the contact points 107 and 60 108 located within the tube 105 and included in the circuit 56. When a cam block 96 is moved by the belt into engagement with the roller 106, the arm 98 and the tube 105 will be tilted to a position to cause the mercury to flow away from the contact points 107 and 108 and open the 65 circuit 56.

The arm 98 and the clamp block 100 are positioned longitudinally upon the shaft 86 by spacing sleeves 109, which extend endwise and abut 70 against the opposite bearing plates 84 and 85. By removing a shaft 86 and rearranging the sleeves 109 upon the shaft 86 the roller 106 of any switch may be positioned to be engaged by the cam blocks 96 located in any of the different

columns through which the cam blocks are moved by the belt.

The longitudinal adjustment of the switches 58 and the rollers 106 upon the shafts 86 is only necessary when rearranging the printing order 5 of the heads 12. To permit the switch tubes 105 to tilt without interfering with each other, the different switch arms 98 are provided with right and left hand sleeves 99, whereby the plates 102 carrying said tubes 105 can be staggered 10 throughout the series of shafts 86 and thus allow the shafts to be placed as closely together as possible, so that a relatively long surface of the control belt 61 will be visible to the operator beyond the series of shafts 86. 15

Each switch 58 comprises a mercury tube switch 105 and controls an electric circuit 56, which circuit also includes a solenoid 50, which in turn controls a latch operating device 31 located adjacent to each printing head 12. 20

When a mercury tube 105, forming a switch 58, is tilted by the weight of the arm 98, to a position in which the roller 106 rests upon a plate 62 of the belt 61, the circuit 56 will be closed, the solenoid 50 will be energized and the 25 latch operating device will be moved to engage the latch 26 with the projection 28 on the head slide 18 and hold the printing head 12 out of action. When the roller 106 is upon a cam block 96 the switch tube 105 will be tilted to a position 30 to open the circuit 56, and the latch 26 will remain out of engagement with the projection 28, and the printing head will be free to be moved down into printing contact with the goods.

The printing blocks 13, on the heads 12, each 35 print a section of the goods 18" long and the strip of goods 15 is moved 18" for each complete revolution of the head operating cams 22. Each plate 62 of the control belt is of a size proportional to an 18" section of the goods and said belt 40 is advanced at a speed proportional to the travel of the goods.

The strip of goods 15 to be printed is of great length and it is desirable to cut the original long strip of goods into shorter strips, of given lengths, 45 so that each shorter strip will exactly fit a drying rack of a given size. If the rack is 96' long the strip when cut should contain sixty-four, 18" rug sections, and to avoid any waste of material the rugs must be completed in sizes to exactly 50 cover the 96' strip. The control belt 61 must always be of a relative length to contain 64 sections, or plates 62, or a multiple of 64 plates.

The shafts 86 and switches 58 extend over only 55 about one-half the length of the top flat surface of the belt 61, the remaining portion of the flat surface of the belt is exposed and presents to the operator a conventional picture, or miniature representation of the rugs before the goods are printed. The exposed surface of the belt 61, 60 with the cam blocks 96 arranged thereon, represents the arrangement of the rugs to be printed, and said surface is visible before the cam blocks pass below the switches 58 for controlling the printing heads. The exposed area of the belt 61 65 is of sufficient length to give the operator ample time to correct mistakes and to change the sizes of the rugs before the goods are printed.

When a defective spot occurs in the goods the operator may readily remove a cam block 96 70 from a section, or plate 62 of the belt, which plate corresponds to the 18" section of the goods where the defective spot occurs. In some cases where large defective spots occur, two or more cam blocks 96 may be removed. The absence of a cam 75

block from the belt will cause the switch 58 to close the circuit 56 so that the latch operating device will latch the printing head associated therewith out of operation.

5 It will be understood that each section, or plate 62, represents 18" of the goods. If a plate 62 does not carry a cam block 96, the corresponding 18" section of the goods will not be printed upon. The cam blocks 96 represent the sections 10 of the goods to be printed, and may be rearranged to change the rug sizes. The positions of the cam blocks 96 in the different columns upon the belt determine the type of printing heads to operate for printing upon the goods.

15 There may be five or more printing heads for printing different colors upon border sections of the rugs, and five or more heads for printing different colors on field sections. Each series of printing heads is controlled by a series of switches 20 58 arranged in rows upon the series of shafts 86. Each row of switches extends parallel with and immediately above a column of the slots 95 formed in the belt plates 62.

The cam blocks 96 positioned in the column of 25 slots indicated in Fig. 3 by the letter A are for operating switches 58 for controlling border type printing heads, for printing either single borders, or double borders, as previously determined. The cam blocks in column B are for operating 30 switches for controlling heads for printing field sections of rugs. The column C is provided for cam blocks for controlling printing heads, not shown on the drawings, for printing center field sections of a different design, and the column D is 35 for signal cam blocks 110.

The signal cam blocks 110 are for operating a 40 signal switch 112 for actuating a signal 113, shown in Fig. 1. Each signal cam block 110 upon the belt indicates the place where the goods are to be cut off to form strips of a given length to be received in a drying rack of a given size, usually 96' long.

The sections, or plates 62, of the belt 61 are 45 numbered 1 to 64, which numbers are not shown on the drawings, said numbers are repeated throughout the length of the belt. A strip of goods may be started into the machine at any point. The number on the control belt plate, corresponding to the starting point of the goods, is 50 noted and a signal cam block 110 is then placed upon every sixty-fourth plate throughout the length of the belt for operating the signal switch 112 and the signal 113.

The signal switch 112 is similar to the switches 55 58, and the switch 112 is included in an electric circuit 114 including the signal device 113, such as an electric bell shown in Fig. 1.

The extensive exposed flat surface of the control belt 61 gives the operator ample time to change 60 the position of the cam blocks 96 without stopping the machine. The signal switch cam blocks 110 indicate to the operator that the strip of goods is to be cut at a certain point and that the goods must be finished with a finishing border at that 65 point and a starting border printed immediately following that point. If one or more 18" sections of defective goods have been omitted from the printing operations the operator can readily change the order of the cam blocks 96 upon the belt before they actuate the switches 58.

70 The operator by inspecting the advancing control belt 61 may see which cam blocks 96 must be shifted for changing the sizes of the rugs to complete a strip of goods which is to be cut off adjacent to the corresponding position of a signal

block 110 on the belt. After the cam blocks 96 have been properly arranged upon the belt between the signal cam blocks 110 the belt will automatically repeat the printing order in which the printing heads are to be operated. It is only 10 necessary to change the arrangement of the blocks 96 when it is required to omit the printing of defective spots occurring upon the goods, or when it is desired to change the sizes of the rugs 15 to be printed.

A manually operated snap-switch 116 is provided in each circuit 56, and said snap-switch is arranged for opening the circuit when a printing head is not to be used and is permanently locked out of action by a hand operated latch well known 15 in the art and not shown in the drawings.

The operation of my invention is as follows: The cams 22 reciprocate the printing heads continuously except when they are held in the elevated position and out of action by the latches 20 26. The cams 22 are set so that they will operate the heads for printing upon every other section of the goods. The goods are then advanced by the machine until the intermediate sections are positioned below the heads to be printed 25 upon, in the usual manner.

The cam arms 32 of the latch operating devices 31 are loosely mounted on the shafts 30 and are moved continuously by the cams 33. The latches 26 are normally out of engagement 30 with the projections 28 of the printing heads. The hooks 36 are released from the cam arms 32 by the weighted ends 39 of the hook levers 31, thus the printing heads may be moved into printing contact with the goods upon every revolution of the shafts 23.

When a circuit 56, including a solenoid 50 of any latch operating device 31 is closed, the hook 36 will be positioned to engage the cam arm pin 49, so that the arm 32 will move the bearing arm 40 35, and the pin 47 on the bearing arm will engage the plate spring 46, which latter will yieldingly move the latch 26 into the path of the projection 28 and hold the head out of action when the latch is engaged with the projection 28. 45

The belt 61 of the control device 60 for actuating the solenoids 50 is moved at a speed proportional to the speed at which the goods 15 are advanced under the printing heads. The transverse plates 62 of the belt, each represents 50 an 18" section of the goods to be printed. There is a switch 58 included in each circuit 56 for operating each solenoid 50. Said switches 58 are arranged to open or close a circuit 56 when the switch is tilted by an arm 98 associated with each 55 switch. When the roller 106 on an arm 98 rests upon the flat surface of a plate 62 of the control belt, the switch 58 will be positioned to close the circuit 56 including a solenoid 50, the latter will be energized and the latch 26 moved by the 60 cam arm 32 into locking position for holding the head 12 out of action.

When the switch arm 98 is tilted by a cam block 96, carried by a belt plate 62, the switch 58 will be actuated to open the circuit 56 and the solenoid 50 will no longer be energized and the latch 26 will be released from the head 12 upon the next revolution of the cam 22.

When a cam block 96 is attached to any plate of the belt, a section of the goods represented by that particular plate will be printed upon by a head 12. A cam block 96 may be readily removed whenever it is desired to prevent the printing of any 18" section of the goods which may be defective. The belt 61 is constructed so 75

that the cam blocks 96 will be carried by the belt in any one of several columns for actuating a series of switches 58 arranged immediately above the different columns. The shafts 86 on which the switches 58 are mounted are separated by a distance equal to two plates 62 of the belt. When a plate 62 does not have a cam block in a particular column all the switch arm rollers 106 which are located over that column 10 will ride upon the flat surface of the belt and said switches will be positioned for closing the circuits 56, thus energizing the solenoids 58 for latching the heads 12 but of printing action.

The switches 58 are all mounted in close relation to each other so as to leave a large flat surface of the belt 61 exposed to view before the cam blocks are advanced below the switches. The exposed portion of the top surface of the control belt presents a miniature representation 20 of the order in which the printing of the successive sections of the goods will take place, and the operator may make various changes in the sizes of the rugs before the printing of the corresponding sections of the goods takes place.

25 When a cam block 96 is removed to prevent the printing of a defective portion of the goods, the operator can see which cam blocks must be shifted from the column of cam blocks which operate the heads for printing field sections of 30 rugs to those for printing border sections, so that complete rugs will be printed before and after the defective sections of the goods occur.

Signal cam blocks 110 are inserted at given intervals upon the belt 61, which blocks 110 35 show the operator where the strip of goods is to be cut to be placed in certain size drying racks. The operator may readily change the cam blocks 96 which are located upon the belt adjacent to the signal cam block 110, so that the 40 last section of the goods will be printed with a finishing border and the new section of goods will be printed with a starting border.

When a new piece of goods is started into the machine the number of the plate of the control belt is noted and the signal cam blocks 110 are attached at intervals throughout the length of the belt, whereby the signal blocks will indicate where the goods are to be cut, and the operator can shift the blocks 96 upon the belt so that each 50 strip of the goods 96' long will contain finished rugs of a salable size.

Various changes in the construction and arrangement of the parts may be made without departing from my invention.

55 I claim:—

1. A printing machine having in combination a frame, means for intermittently advancing goods into the machine to be printed, printing heads, means for reciprocating the heads into printing relation with the goods, a latch movably mounted upon the frame adjacent to each head for latching the head out of action, a bearing arm mounted for oscillation and operatively associated with the latch for engaging the latter with the head, a part mounted for oscillation in timed relation with the head, locking means upon the bearing arm and arranged for engagement with said part, an electromagnetic device mounted upon said arm and arranged for engaging said locking means with said part for moving said arm with said part, and a control device operatively associated with said electromagnetic device.

2. A printing machine having in combination a 75 frame, means for intermittently advancing goods

to be printed, reciprocating printing heads, a latch movably mounted upon the frame adjacent to each head and arranged for holding a head out of printing contact with the goods, a bearing arm mounted for oscillation, a hook lever pivoted upon the said arm, a part mounted for oscillation in timed relation with the head, an electro-magnetic device mounted upon said arm and arranged for moving said hook lever into locking engagement with said part for moving the bearing arm with said part, flexible means actuated by the bearing arm for engaging the latch with the head, and a control device operatively associated with said electro-magnetic device.

3. A printing machine having in combination 15 a frame, reciprocating printing heads upon the frame, a latch movably mounted upon the frame and located adjacent to each head, a shaft upon the frame, an arm mounted upon the shaft, means for oscillating said arm in timed relation 20 with the head, a bearing arm pivotally mounted upon the shaft, means for coupling the bearing arm for movement with said first mentioned arm, and means operatively associated with the bearing arm and the latch and arranged for engaging 25 the latch with the printing head for holding the latter inoperative.

4. A printing machine having in combination a frame, reciprocating printing heads upon the frame, a latch movably mounted upon the frame 30 and located adjacent to each head, a shaft upon the frame, an arm mounted upon the shaft, means for oscillating said arm in timed relation with the head, a bearing arm pivotally mounted upon the shaft, means for coupling the bearing 35 arm for movement with said first mentioned arm, a flexible member having one end pivoted upon the shaft, means upon the bearing arm engageable with said member and arranged for rotating said member into engagement with the latch and 40 positioning the latter for holding the printing head inoperative, and means upon the bearing arm arranged for actuating said means for coupling the bearing arm with the first mentioned arm.

5. A printing machine having in combination, printing heads, means for intermittently advancing goods under said heads, shafts, cams upon said shafts for reciprocating the heads into printing relation with the goods, a latch associated 50 with each head for latching the head out of operation, individual mechanical means for operating each latch said means having an electromagnetic device adapted for coupling said mechanical means with each latch, an electric circuit 55 including the electro-magnetic device, a control device operatively associated with said electro-magnetic device, a belt included in the control device, means for moving the belt in timed relation with the speed of the goods, said belt 60 having a variable surface, a circuit controlling device in the circuit including the electro-magnetic device, means for operating said circuit controlling device by the variable surface of the belt, and means for varying the surface of the belt 65 whereby the operation of all the printing heads is controlled.

6. A printing machine having in combination a frame, printing heads, slides movable vertically upon the frame and carrying said heads, a latch 70 movable to and from engagement with said slide for holding the head out of action when said latch is engaged with the slide, a cam shaft upon the frame, a cam upon said shaft for lifting the slide, a second cam upon said shaft, a second 75

shaft mounted upon the frame, means securing the latch upon said second shaft, an arm pivoted upon the second shaft and movable by said second cam, a bearing arm pivoted upon the second shaft, a part associated with said bearing arm and arranged to rotate the second shaft and engage the latch with said slide, a hook pivoted upon said bearing arm, a solenoid mounted upon said bearing arm and arranged for engaging the hook with the first mentioned arm, an electric circuit including the solenoid, a switch included in said circuit, and a control device arranged for actuating the switch.

7. A printing machine having in combination a frame, printing heads, slides movable vertically upon the frame and carrying said heads, a latch movable to and from engagement with said slide for holding the head out of action when said latch is engaged with the slide, a cam shaft upon the frame, a cam upon said shaft for lifting the slide, a second cam upon said shaft, a second shaft rotatably mounted upon the frame, an arm loosely pivoted upon the second shaft and movable by said second cam, a bearing arm loosely pivoted upon said second shaft, a flexible arm secured upon said second shaft and movable by the bearing arm into engagement with the latch for positioning the latter for engagement with the slide, a solenoid mounted upon the bearing arm, locking means upon said bearing arm and arranged to be actuated by the solenoid for locking the bearing arm with the cam arm, an electric circuit including the solenoid, a switch included in said circuit, and a control device arranged for actuating the switch.

8. A printing machine having in combination, printing heads, means for intermittently advancing the goods under said heads, shafts, cams upon said shafts for reciprocating the heads into printing relation with the goods, a second shaft mounted for rotation and located adjacent to each head, a latch secured to said second shaft and associated with each head for latching the head out of printing operation, an arm loosely mounted upon said second shaft, means for oscillating the arm in timed relation with the head with which the second shaft is associated, a bearing arm loosely mounted upon said second shaft, means upon the bearing arm adapted for rotating the second shaft with the bearing arm, an electro-magnetic device mounted upon said bearing arm and adapted for locking the latter with the first-mentioned arm, an electric circuit including the electro-magnetic device, a control device operatively associated with said electro-magnetic device, a belt included in the control device, means for moving the belt in timed relation with the goods, said belt having a variable surface, a mercury switch in the circuit including the electro-magnetic device, means for operating the mercury switch by the variable surface of the belt, and means for varying the surface of the belt whereby the operation of the printing heads is controlled.

65 9. A printing machine having in combination, means for intermittently feeding goods into the machine, printing heads, means for reciprocating the heads for printing upon the goods, a latch associated with each head for latching the head out of printing operation, latch operating means associated with each latch, a control belt, means for moving the belt at a speed proportional to the speed of the goods, latch controlling means located adjacent to the belt and operatively associated with the belt and

5 plates secured upon the belt and positioned transversely relatively to the length of the belt, cam blocks movable with the belt into operative engagement with said latch controlling means, and means detachably mounting the cam blocks upon said plates.

10. A printing machine having in combination a frame, means for intermittently feeding goods into the machine, printing heads, means for reciprocating the heads for printing rug sections upon the goods, a latch associated with each head for latching the head out of printing operation, latch operating means associated with each latch, a control belt, means for moving the belt at a speed proportional to the speed of the goods, latch controlling means located adjacent to the belt and operatively associated with said latch operating means, transverse plates mounted upon the belt, each plate forming a belt section proportional in size to a section of the goods to be printed, cam blocks movable with the belt into operative engagement with said latch controlling means, and cooperating fastening means upon the cam blocks and upon said plates and arranged to permit the ready removal or attachment of said cam blocks to said plates.

11. A printing machine having in combination a frame, means for intermittently feeding goods into the machine, printing heads, means for reciprocating the heads for printing rug sections upon the goods, a latch associated with each head for latching the head out of printing operation, latch operating means associated with each latch, a control belt, means for moving the belt at a speed proportional to the speed of the goods, latch controlling means located adjacent to the belt and operatively associated with said latch operating means, means slidably supporting said controlling means in adjusted positions transversely to the belt and in different rows according to the type of heads to be operated, said rows extending parallel with the direction of travel of the belt, transverse plates mounted upon the belt, each plate forming a belt section proportional in size to a section of the goods to be printed, each plate being provided with a series of fastening means thereon, each of said fastening means positioned upon a plate so as to align with said latch controlling means, cam blocks adapted for actuating said controlling means, and fastening means upon each cam block and arranged for detachably mounting said cam blocks upon said plates.

12. A printing machine having in combination a frame, means for intermittently feeding goods into machine, printing heads, means for reciprocating the heads for printing rug sections upon the goods, a latch associated with each head for latching the head out of printing operation, latch operating means associated with each latch, a control belt, means for moving the belt at a speed proportional to the speed of the goods, latch controlling means located adjacent to the belt and operatively associated with said latch operating means, said controlling means arranged in different rows according to the type of heads to be operated, said rows extending parallel with the direction of travel of the belt, transverse plates mounted upon the belt, each plate forming a belt section proportional in size to a section of the goods to be printed, each plate provided with slots and located at spaced intervals throughout the length of each plate, cam blocks adapted to be placed upon a plate adjacent to one of said slots and carried by the belt

into operative engagement with said latch controlling means, and fastening means upon each cam block arranged to enter a slot formed in a plate and detachably secure the cam block upon a plate.

13. A printing machine having in combination a frame, means for intermittently feeding goods into the machine, printing heads, means for reciprocating the heads for printing rug sections upon the goods, a latch associated with each head for latching the head out of printing operation, latch operating means associated with each latch, a control belt, means for moving the belt at a speed proportional to the speed of the goods, latch controlling means located adjacent to the belt and operatively associated with said latch operating means, plates secured upon the belt and positioned transversely relatively to the length of the belt, said plates each having a slot formed therein, cam blocks, and a spring plate secured to each cam block and arranged to enter the slot formed in a plate and detachably secure the cam block upon the belt for actuating said latch controlling means.

14. A printing machine having in combination a frame, means for intermittently advancing goods into the machine, printing heads, means for reciprocating the heads for printing rug sections upon the goods, a latch associated with each head for latching the head out of printing action, latch operating means associated with each latch, latch controlling means operatively associated with each latch operating means, an endless control belt, transverse plates mounted upon said belt, said plates each being proportional to a rug section of the goods to be printed, cam blocks mounted upon said plates and arranged for actuating said controlling means when advanced by the belt into engagement with the controlling means, said belt having a flat surface exposed to view in advance of said controlling means and containing a sufficient number of said plates with the cam blocks thereon corresponding to a plurality of complete rug patterns graphically presented upon the exposed portion of the belt.

15. A printing machine having in combination a frame, means for intermittently advancing goods into the machine, printing heads, means for reciprocating the heads for printing rug sections upon the goods, a latch associated with each head for latching the head out of printing action, latch operating means associated with each latch, latch controlling means operatively associated with each latch operating means, an endless belt, wheels upon which the belt is mounted, a table located between said wheels and supporting a straight run of the belt, plates secured upon the belt and positioned transversely to the length of the belt, said plates located adjacent to each other and each forming a section of the belt proportional in size to a section of the goods to be printed, cam blocks, means detachably mounting a cam block upon a plate, said controlling means located adjacent to the belt and arranged to be actuated by said cam blocks as they are advanced by the belt into operative engagement with said controlling means, said controlling means occupying a portion of the length of the table, said table having a portion extending beyond said controlling means for exposing to view a sufficient number of plates to graphically represent a plurality of complete rugs upon the belt before the plates are advanced by the belt adjacent to said controlling means whereby the cam blocks

may be rearranged upon the plates for changing the rug sections to be printed by the heads.

16. A printing machine having in combination a frame, means for intermittently advancing goods into the machine, printing heads, means for reciprocating the heads for printing rug sections upon the goods, a latch associated with each head for latching the head out of printing action, electro-magnetic devices controlling the latches, an endless belt, means moving the belt at a speed proportional to the speed of the goods, plates mounted upon the belt and positioned transversely relatively to the length of the belt, said plates positioned adjacent to each other and forming a continuous supporting surface upon the belt, arms pivotally mounted adjacent to the belt and having their free ends riding upon said surface, cam blocks upon said plates and arranged for tilting the arms, electric circuits each including one of said electro-magnetic devices, a switch controlling each of said circuits, and means mounting each switch for operation by the tilting of the arm.

17. A printing machine having in combination a frame, means for intermittently advancing goods into the machine, printing heads, means for reciprocating the heads for printing rug sections upon the goods, a latch associated with each head for latching the head out of printing action, an electro-magnetic device controlling each latch, an electric circuit including said device, a mercury switch included in each circuit for opening and closing the same, an endless belt, means moving the belt at a speed proportional to the goods, transverse plates mounted upon the belt, cam blocks detachably mounted upon said plates, arms pivotally mounted adjacent to the belt and having their free ends movable by the cam blocks, means operatively associating a mercury switch in operative relation with an arm, means supporting a straight run of the belt with a flat surface exposed to view in advance of said arms, and said flat surface of the belt containing a number of said plates with the cam blocks thereon corresponding to a complete pattern to be printed upon the goods by said heads.

18. A printing machine having in combination a frame, means for intermittently advancing goods into the machine, printing heads, means for reciprocating the heads for printing rug sections upon the goods, a latch associated with each head for latching the head out of printing action, an endless belt, means advancing the belt at a speed proportional to the speed of the goods, cam blocks detachably mounted upon the belt, bearing plates positioned adjacent to and at opposite sides of the belt, shafts mounted in said bearing plates and extending transversely relatively to the length of the belt, an arm slidably mounted upon each shaft, means for securing the arm relatively to the length of the shaft for locating the free end of the arm in alignment with a cam block, and control devices arranged to be actuated by the tilting of the arms.

19. A printing machine having in combination a frame, means for intermittently advancing goods into the machine, printing heads, means for reciprocating the heads for printing rug sections upon the goods, a latch associated with each head for latching the head out of printing action, an endless belt, means advancing the belt at a speed proportional to the speed of the goods, cam blocks detachably mounted upon the belt, bearing plates positioned adjacent to and at op-

posite sides of the belt, shafts mounted in said bearing plates and extending transversely relatively to the length of the belt, an arm pivotally mounted upon each shaft and having its free 5 end located adjacent to the belt and in alignment with a cam block, and a signal device arranged to be actuated by the tilting of one of said arms when engaged by a cam block.

20. A block printing machine having in combination a frame, reciprocating heads, means for intermittently advancing a continuous strip of goods to be printed by said heads, an endless belt comprising sections each section being proportional in size to the length of a section of the 10 goods to be printed by a head, cam blocks detachably mounted upon said sections of the belt and arranged to control the printing operation of the printing heads, said cam blocks arranged in series and positioned in different columns, said columns extending throughout the length of the belt, a signal device, one column of the belt having a cam block for operating said signal device after a given number of said sections of the goods 15 have been printed by said print heads.

25. 21. A block printing machine having in combination a frame, reciprocating printing heads, means for intermittently advancing a continuous strip of goods to be printed by said heads, an endless belt comprising sections each section being proportional in size to the length of a section of the 20 goods to be printed by a head, cam blocks detachably mounted upon said sections of the belt and arranged to control the printing operation of the printing heads, said cam blocks arranged in different columns extending throughout the length of the belt, a signal device for indicating when a given length of the goods has been 25 printed, signal device operating cam blocks positioned in a separate column upon the belt and arranged for operating said signal device, said signal device cam blocks spaced apart distances proportional to the length of said given lengths of the goods to be printed.

22. A printing machine having in combination 30 a frame, means for intermittently advancing goods into the machine, printing heads, means for reciprocating the heads for printing rug sections upon the goods, a latch associated with each head for latching the head out of printing action, 35 an endless belt, means advancing the belt at a speed proportional to the speed of the goods, plates positioned upon said belt and extending transversely relatively to the length of the belt, cam blocks detachably mounted upon said plates, 40 said cam blocks arranged in different columns relatively to the length of the belt, bearing plates positioned adjacent to and at opposite sides of the belt, shafts having their opposite

ends mounted in said bearing plates and extending lengthwise at right angles to the length of the belt, an arm pivotally mounted upon each shaft and having its free end located adjacent to the belt, spacing sleeves upon said shafts and arranged for locating the arm in alignment with a cam block, and control devices arranged to be actuated by the tilting of the arms.

23. A printing machine having in combination a frame, printing heads, slides movable vertically 10 upon the frame and carrying said heads, means for advancing goods to be printed by said heads, a latch upon the frame and movable into and out of locking engagement with a slide, a cam shaft upon the frame, a cam upon said shaft for lifting 15 the slides, a second cam upon said shaft, a cam arm movable by said second cam, a shaft upon the frame and upon which said arm is loosely pivoted, a bearing arm loosely pivoted upon the last mentioned shaft, locking means upon the 20 bearing arm and engageable with the cam arm for moving the bearing arm with the cam arm, a part operatively associated with the bearing arm and the latch for moving the latter into engagement with said slide, a solenoid upon the bearing arm and arranged for operating said locking means, a belt, means for moving the belt at a speed proportional to the goods, plates mounted upon said belt and positioned transversely to the length of the latter, cam blocks, means detachably mounting said blocks upon said plates, shafts located upon the frame and in spaced relation to the belt and positioned transversely to the length of the belt, arms loosely mounted upon said last mentioned shafts and arranged to be tilted by 25 said cam blocks, a mercury switch mounted upon each of said last mentioned arms, and electric circuits each including a mercury switch and a solenoid.

24. A printing machine having in combination 30 a frame, means for intermittently advancing goods into the machine, printing heads arranged for printing successive rug sections upon the goods to form complete rugs, means operatively associated with the heads and arranged for latching the heads into and out of printing operation, an endless control belt formed of hinged belt sections proportional in size to said rug sections, means for advancing the belt at a speed proportional to the speed of the goods, means 35 upon said belt sections and arranged for controlling the latching of said heads, and means mounting said belt to present a surface exposed to view and containing upon said exposed surface a number of said belt sections corresponding 40 to a plurality of complete rugs.

OSCAR BROPHY.
